US00D972146S

(12) **United States Design Patent** (10) **Patent No.:** **US D972,146 S**
Asmussen et al. (45) **Date of Patent:** **** Dec. 6, 2022**

(54) **EAR PLUG**

(71) Applicant: **Ear Labs AB**, Malmö (SE)

(72) Inventors: **Casper Asmussen**, Malmoe (SE);
Aleksandar Andreevski, Malmoe (SE);
Tina Elise Brattgjerd Alnæs,
Stockholm (SE)

(73) Assignee: **Ear Labs AB**, Malmö (SE)

(**) Term: **15 Years**

(21) Appl. No.: **35/513,028**

(22) Filed: **Nov. 8, 2021**

(80) **Hague Agreement Data**

Int. Filing Date: **Nov. 8, 2021**

Int. Reg. No.: **DM/217467**

Int. Reg. Date: **Nov. 8, 2021**

Int. Reg. Pub. Date: **Nov. 26, 2021**

(30) **Foreign Application Priority Data**

May 19, 2021 (EM) 008546766-0001

(51) **LOC (13) Cl.** **24-99**

(52) **U.S. Cl.**

USPC **D24/174; D14/223**

(58) **Field of Classification Search**

USPC D24/173, 174; D14/223, 205; D29/112;
2/209; 600/474, 549; 381/380-381, 328

(57) **CLAIM**

The ornamental design for an ear plug, as shown and described.

DESCRIPTION

1. Ear plug
- 1.1: Front top perspective view
- 1.2: Front view
- 1.3: Right side view
- 1.4: Rear view
- 1.5: Left side view
- 1.6: Bottom view
- 1.7: Top view

1 Claim, 7 Drawing Sheets
